MOLLIE BRAUNSTEIN, OF CEDARHURST, NEW YORK

DOUBLE CUFF FOR KNICKERS AND THE LIKE, AND PROCESS FOR ITS MANUFACTURE

Application filed February 26, 1931. Serial No. 518,339.

This invention relates to new and useful improvements in a double cuff for knickers and the like, and a process for manufacturing it.

At the present time there is very keen competition among manufacturers of cuffs for knickers, and each is striving to create a cuff which has better wearing qualities than their competitors. The purpose of this is to gain a selling advantage over their rivals.

At the present time in the trade, it is generally known to manufacture cuffs of double material which are bent up at the bottom so that the ends are adjacent each other at the top. It is usual to place such cuffs upon the bottom ends of knicker legs, so that the top ends of the cuff are on opposite sides of the material of the knicker legs. The cuffs thus constructed are not flared and consequently do not fit the natural formation of the garment. Further, rough top edges are exposed. Another construction generally used is cuffs formed of double material bent at the bottom so as to have an inside layer which does not extend completely to the top of the outside layer. The latter layer at the top is flared so as to properly fit upon the knicker legs. This arrangement is unsatisfactory in that the portion needing the greatest strength, that is, the portion which is attached to the knicker legs, is the weakest since it is of single material.

It is an object of this invention to construct a double cuff which is made from double material bent down at the top and up at the bottom so as to have its edges adjacent each other. In this manner the entire length of the cuff is of double material. It is also proposed to knit the material so that when the ends are bent as just directed a flared top portion is produced for the cuff. A cuff thus constructed is finished at both ends and is strong at the point where it connects with the knickers. Further, the adjacent arrangement of the edges serve to shield each other and prevent opening up of the stitches which are used to hold them down.

As another object of this invention it is proposed to arrange the edges of the cuff which are formed by turning the top down or

the bottom up anywhere between the length of the cuff so as to be either in the flared portion or at the junction of the flared portion with the tubular portion, or any place along the tubular portion itself.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a front elevational view of a cuff 65 constructed according to this invention.

Fig. 2 is an edge elevational view of Fig. 1.

Fig. 3 is a plan view of Fig. 1.

Fig. 4 is a sectional view taken on the line 4—4 of Fig. 1.

Fig. 5 is a fragmentary sectional view taken on the line 5—5 of Fig. 3.

Fig. 6 is a developed view of the material used in forming the cuff, and

Fig. 7 is a view similar to Fig. 5, but illustrating a modification.

The double cuff according to this invention is made from a tubular piece of knitted material 10 having anywhere along its length a bulged portion 11. It is possible to construct such pieces on customary knitting machines. The process of forming such pieces consists in knitting the tubular material until the portion where the bulge is desired, and then making certain adjustments on the knitting machine so as to form stitches known in the trade as cardigan. The attachment first loosens the stitches until the greatest diameter of the bulge is formed and then tightens the stitches to a point where the material is 80 of its initial diameter again.

In Fig. 6 the bulge 11 has been shown spaced slightly down from the top. When thus constructed to form the cuff, as illustrated in Figs. 1 to 5, it is necessary to bend the material down upon the line indicated by the dot and dash line 12, and to bend the bottom end of the material up along the dot and dash line 13. When this is done, the free ends 14 of the material will be adjacent each 95 100

other within the cuff. The cuff, as concluded, is of double material with a bend 15 at the bottom and a bend 16 at the top. The lower portion of the cuff, indicated by reference numeral 17, is of tubular form, while the upper portion 18 is flared. The top edge 19 of the cuff naturally comes out arched as shown in Fig. 1 when the cuff is flat, as shown on the drawings.

10 In Fig. 5 it should be particularly noticed, the manner in which the doubled flared material lays, that is, the layers forming the doubled material are immediately adjacent each other and of shapes so as to be flat 15 against each other. The cuff may be finished by stitches 20 for holding down the ends 14. These stitches should be of the type which can stretch, so as not to hinder the stretching qualities of the cuff.

20 In Fig. 7 a modified form of the cuff has been illustrated, which is practically identical with the preferred form except that the ends 14 of the material forming the cuff are located at a different position than that shown 25 in the preferred form. In this case the ends are located at the junction between the flared and the tubular portion of the cuff. The ends according to this invention may be located any place along the length of the 30 cuff. Of course, when located in different positions, it will be necessary that the blank from which the cuff is made, be properly knitted so that the top end may be folded down and the bottom end be folded up and 35 the cuff thus formed with the flared portion coming out right.

10 In use, the cuff may be attached upon knickers, sleeves or other cuffs. The various advantages gained according to the instant invention is that the cuff is of uniform thickness throughout its length. Further, that the cuff is of double thickness throughout its length so as to have uniform elastic properties. The top edge of the cuff at which it is attached to the garment is also of double 15 thickness so that its strength is substantial. Both ends of the cuff are finished in that they are turned inwards exposing just bent portions. The adjacent ends 14 of the cuff preferably should be quite close together, so that 20 when stitched down one serves to shield the other.

It should be recognized that when a garment provided with the cuff is placed on a 25 wearer, the foot or the hand passes through the cuff. Such passage may tend to place strains upon the inner edge of the cuff and thus tend to break the stitches, but according to the instant arrangement one of the 30 edges of the cuff shields the other edge so that it is impractical that there will be any possibility of stresses tending to pry the edges free.

While I have illustrated and described my 35 invention with some degree of particularity, I realize that in practice various alterations

therein may be made. I therefore reserve the right and privilege of changing the form of the details of construction or otherwise altering the arrangement of the correlated parts without departing from the spirit or 70 the scope of the appended claims.

Having thus described my invention, what I claim as new, and desire to secure by United States Letters Patent is:—

1. A process for manufacturing a double 75 cuff for knickers and the like, consisting in knitting tubular material with a bulged portion, then bending the top down within the tubular material and the bottom up also within the tubular material.

2. A process for manufacturing a double 80 cuff for knickers and the like, consisting in knitting tubular material with a bulged portion, then bending the top down within the tubular material and the bottom up also within the tubular material, said bulged portion being formed by cardigan stitches.

3. A process for manufacturing a double 85 cuff for knickers and the like, consisting in knitting material into tubular form with an intermediate portion of cardigan stitches so that a bulge occurs, bending down the tubular material along a line of greatest width on 90 said bulge, and bending up the bottom of the tubular material so that the ends are substantially adjacent each other.

4. A double cuff for knickers and the like, 95 comprising a single thickness of knitted material of substantially tubular form and having a section a portion of which diverges and the other portion converges, both ends of the tubular form being turned inwards and one of said ends being bent along the line dividing the diverging and converging portions.

100 5. A double cuff for knickers and the like, comprising a single thickness of knitted material of substantially tubular form and having a section a portion of which diverges and the other portion converges, both ends of the tubular form being turned inwards and one of said ends being bent along the line dividing the diverging and converging portions, the bent ends being substantially adjacent each other.

105 6. A double cuff for knickers and the like, comprising a single thickness of knitted material of substantially tubular form and having a section a portion of which diverges and the other portion converges, both ends of the tubular form being turned inwards and one of said ends being bent along the line dividing the diverging and converging portions, the bent ends connecting the ends with the material immediately adjacent.

110 Signed at New York in the county of New York and State of New York, this 24th day of February A. D. 1931.
